To all whom it may concern:

Be it known that I, Fannie Sussman, a citizen of the United States, residing in New York city, in the county of New York and State of New York, have invented a new, original, and ornamental Design for a Dress Ensemble, of which the following is a specification, reference being had to the accompanying drawing, forming part thereof.

The characteristic feature of my design resides in the combination on the ensemble disclosed of the specific, bishop sleeved, bolero member which is embroidered as shown.

I claim:
